LOCKING AND VENTILATING MEANS FOR
HATCH COVERS

Earl R. Swanson, Chicago, Ill., assignor to Standard Railway Devices Company, Chicago, Ill., a corporation of Delaware

Application April 15, 1942, Serial No. 438,990

4 Claims. (Cl. 98—7)

This invention relates to refrigerator cars and more particularly to overhead bunker cars where-in a plurality of refrigerant containers are supported immediately below the roof of the car. Such containers commonly cover substantially the entire plan of the car and consequently each container has a large area and is relatively shallow. Hatches of the size usually provided in refrigerator cars have a small area relative to such a container and it is, therefore, difficult to load refrigerant into all parts of the containers. My invention is adapted for use with the double hatch arrangement disclosed, which arrangement may be considered either as two adjacent hatches or, viewed from another angle, as one large hatch divided into two parts by a strut. Separate covers are provided for each of the hatches and are preferably hinged to upstanding roof carlines remote from the strut which separates the hatches.

An object of the invention is to provide unitary means for simultaneously moving both covers to their tightly closed positions by a single movement of said unitary means.

Hatch covers are often difficult to open due to the fact that the gasket or padding becomes wedged into the hatch frame; to the fact that the covers and frames are sometimes coated with ice; and to numerous other causes. An object of my invention is to utilize the above mentioned unitary means to simultaneously break the seals and partially open both of the hatch covers.

A further object is to utilize the above mentioned unitary means for supporting either hatch cover in a partly open position, commonly used for ventilation, and at the same time to lock the other cover in a closed position.

Other objects and advantages of my invention will be apparent from the following detailed description by referring to the accompanying drawings.

In the drawings:

Fig. 1 is a partial plan view of the roof of a refrigerator car showing a double hatch arrangement equipped with locking and ventilating means which illustrates the preferred embodiment of my invention.

Fig. 2 is a section on line 2—2 of Fig. 1.

Fig. 3 is an enlarged view of a portion of Fig. 1.

Figs. 4 and 5 are sections on lines 4—4 and 5—5, respectively, of Fig. 3.

The drawings disclose the roof 2 of a refrigerator car having a hatch frame 3 with a strut 5 extending thereacross to form a pair of adjacent hatches 4. A refrigerant container 6 is disposed

immediately below the hatches 4 and has a length somewhat longer than the combined length of the hatches. The covers 8, 9 for the hatches are preferably mounted by means of hinges 11 disposed oppositely from the strut 5 and attached to the upstanding roof carlines 12. The covers 8, 9 are preferably insulated and provided with resilient padding 14 which is compressed against the hatch frame 3 and strut 5 when the covers are closed to form an air tight and heat insulating seal.

An upstanding pintle 20 is rigidly attached to the strut 5 between the hatches and a member 21 is swivelably mounted upon the pintle 20 and retained thereon by a washer 23 held by a screw 24, which washer 23 overlies a shoulder of the member 21. The member 21 is provided with rigid knobs 27 projecting therefrom in diametrically opposite directions, although it is to be understood that the knobs 27 could be replaced by rollers without departing from my invention.

A member 30 is rigidly carried by each cover, 8, 9 which member projects beyond the edge of the cover and includes a cam slot 31 which, when shown in plan as in Fig. 3, has a curved shape which substantially follows the path of the knobs 27 during rotation of the member 21. The slots 31 are higher at their centers than at their ends so that as a knob 27 moved through a slot 31, the cover is forced to a tightly closed position as the knob reaches the center of the slot and is partly open as the knob approaches either end of the slot. Fig. 3 shows the knobs 27 at the centers of the slots 31 and the covers 8, 9 consequently tightly closed.

A ventilating bar 35 is pivotally mounted (34) upon the upper part of the member 21 so as to swing about a horizontal axis transverse to the axis of the knobs 27. When the covers 8, 9 are closed, the bar 35 overlies either of the covers 8 or 9. (The bar is illustrated above the cover 9 as shown most clearly in Fig. 5.) The members 30 carried by the covers 8, 9 have upstanding webs 36 each having two holes 38, 39 of which one (38) is aligned with the hole 41 in the ventilating bar 35 when the covers are closed and the bar 35 overlies one of the covers. The conventional U-shape locking pin 42 may be inserted and sealed in the usual manner.

In order to open the covers 8, 9, the member 21 is rotated 90° upon its substantially vertical axis, using the bar 35 to provide sufficient leverage to rotate the member 21. The knobs 27 then move clear of the cam slots 31 but during such movement slightly lift the covers 8, 9 so as to

break their seals with the hatch frame 3; the covers may then be easily opened by hand. To open the cover 9a to a ventilating position, such cover is lifted until the cam slot 31 associated therewith is above the path of the knobs 27. The member 21 is then rotated 90°, thereby engaging a knob 27 with the cam slot 31 of the closed cover 8 and tightly closing such cover. The bar 35 is then raised to the substantially vertical position shown by phantom lines in Fig. 5 and the edge of the member 30 carried by the cover 9a is then seated upon the desired step 45 of the ventilating bar 35. The partly open cover 9a is locked in this ventilating position by insertion of the U-shaped pin 42 through the proper hole 46 in the bar 35. Either cover may thus be locked in its partly open position and the other cover simultaneously locked in its tightly closed position.

The accompanying drawings illustrate the preferred form of the invention, though it is to be understood that the invention is not limited to the exact details of construction shown and described, as it is obvious that various modifications thereof within the scope of the claims, will occur to persons skilled in the art.

I claim:

1. In a refrigerator car, a pair of hatches in the roof thereof, a strut between said hatches, covers for said hatches separately hinged to said roof, unitary locking means for both of said covers mounted upon said strut and comprising a member pivotally mounted to swing upon a substantially vertical axis, means to swing said member, oppositely projecting knobs on said member and cams carried by said covers having slots in the path of said knobs, said slots being inclined downwardly toward their ends so that the covers are tightly closed when the knobs are adjacent the centers of the slots and opened as the knobs approach the ends of the slots.

2. In a refrigerator car, a pair of hatches in the roof thereof, a strut between said hatches, covers for said hatches separately hinged to said roof, unitary locking and ventilating means for

both of said covers mounted upon said strut and comprising a member pivotally mounted to swing upon a substantially vertical axis, oppositely projecting knobs on said member, cams carried by 5 said covers engageable with said knobs to open or close said covers upon pivotal movement of said member, a locking and ventilating bar pivotally mounted on said member to swing upon a substantially horizontal axis and means associated with said ventilating bar to support either of said covers in partly open position.

3. In a refrigerator car, a pair of hatches in the roof thereof, a strut between said hatches, covers for said hatches separately hinged to said 15 roof, unitary locking and ventilating means for both of said covers mounted upon said strut and comprising a member pivotally mounted to swing upon a substantially vertical axis, oppositely projecting knobs on said member, cams carried by 20 said covers engageable with said knobs to open or close said covers upon pivotal movement of said member, a locking and ventilating bar pivotally mounted on said member to swing upon a substantially horizontal axis and means associated with said ventilating bar to support either of said covers in partly open position, one of said knobs and cams cooperating at the same time to hold the other of said covers closed.

4. In a refrigerator car, a pair of hatches in 30 the roof thereof, a strut between said hatches, hinged covers for said hatches having their free edges opposite the hinged edges adjacent said strut, unitary locking and ventilating means for both of said covers mounted upon said strut and 35 comprising a member pivotally mounted to swing upon a substantially vertical axis, oppositely projecting knobs on said member, cams carried by said covers engageable with said knobs to open or close said covers upon pivotal movement of 40 said member, a locking and ventilating bar pivotally mounted on said member to swing upon a substantially horizontal axis and means associated with said ventilating bar to support either of said covers in partly open position.

EARL R. SWANSON.
